CLAIM

The ornamental design for a dual arm monitor stand, as shown and described.

DESCRIPTION

FIG. 1 is a perspective view of a dual arm monitor stand showing my new design in a first configuration;

FIG. 2 is a perspective view of the dual arm monitor stand in a second configuration;

FIG. 3 is a front elevational view of FIG. 1;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines immediately adjacent to the claim depict the bounds of the claimed design, while all other broken lines are directed to environment. The broken lines form no part of the claimed design. The wire frame lines shown throughout the views indicate surface contour. The "NB North Bayou" lettering and icon forming part of the disclosure is a registered trademark of KUNSHAN HONGJIE ELECTRONICS CO., LTD.
